UNITED STATES PATENT OFFICE.

ARTHUR P. WITTEN, OF AKRON, OHIO.

DESIGN FOR A TOY FIGURE.

Application filed April 7, 1922. Serial No. 1,622. Term of patent 3½ years.

To all whom it may concern:

Be it known that I, ARTHUR P. WITTEN, a citizen of the United States, residing at Akron, in the county of Summit and State of Ohio, have invented a new, original, and ornamental Design for a Toy Figure, of which the following is a specification, reference being had to the accompanying drawings, forming a part thereof.

I claim:

The ornamental design for a toy figure as shown.

ARTHUR P. WITTEN.
